(57) **CLAIM**

The ornamental design for a buckle, as shown and described.

DESCRIPTION

FIG. 1 is a perspective view of the buckle showing a first embodiment of my new design;

FIG. 2 is a front-elevational view of the embodiment of FIG. 1;

FIG. 3 is a rear view of the embodiment of FIG. 1;

FIG. 4 is a top-plan view of the embodiment of FIG. 1;

FIG. 5 is a bottom-plan view of the embodiment of FIG. 1;

FIG. 6 is a right-side view of the embodiment of FIG. 1, the left side view being a mirror image thereof;

FIG. 7 is a cross-sectional view of the embodiment of FIG. 1 taken along the line 7—7 in FIG. 2;

FIG. 8 is a front view of a male member of the embodiment of FIG. 1;

FIG. 9 is a rear view of the male member of FIG. 8;

FIG. 10 is a right-side view of the male member of FIG. 8, the left-side view being a mirror image thereof;

FIG. 11 is a top-plan view of the male member of FIG. 8;

FIG. 12 is a bottom-plan view of the male member of FIG. 8.

FIG. 13 is a front-elevational view of a female member of the embodiment of FIG. 1;

FIG. 14 is a rear view of the female member of FIG. 13;

FIG. 15 is a right-side view of the female member of FIG. 13, the left-side view being a mirror image thereof;

FIG. 16 is a top-plan view of the female member of FIG. 13; and,

FIG. 17 is a bottom-plan view of the female member of FIG. 13.
